Application May 22, 1935, Serial No. 22,778

34 Claims. (Cl. 200—144)

My invention relates to an arc extinguisher for a circuit breaker of the type in which the arc is split up into a series of short arcs between conducting plates on which the short arcs are rotated about an annular path by a radial magnetic field.

An object of my invention is to provide an arc extinguisher of this type which is capable of extinguishing arcs carrying high currents.

10 Another object of my invention is to provide an arc extinguisher in which the arc is split longitudinally into a plurality of parallel-connected arcs for the whole length of the arc between its terminals.

15 A further object of my invention is to provide an arc extinguisher in which the parallel-connected arcs are each divided into a plurality of series-related arcs which are then rotated by a magnetic field about annular paths until the arcs 20 are extinguished.

25 A further object of my invention is to provide an arc extinguisher comprising a series of spaced plates of conducting material having slots therein in which the arc is moved. These slots have two diverging branches at one end thereof towards which the arc is moved and caused to be split into two parallel-related arcs before the arc is split up into series-related arcs between the spaced conducting plates. By first causing the arc to play 30 as two parallel-connected arcs, the arcs may be caused to split up into series-related arcs much more easily without burning the tips of the slots.

35 This invention is a further improvement on arc extinguishers for circuit breakers of the type disclosed in Slepian Patent No. 1,927,904 issued September 26, 1933. In arc extinguishers of the type where the arc is moved into a slot in a stack of spaced plates of conducting material and is split up into short series-related arcs between the 40 plates when the arc reaches the tips of the slots, difficulty has been experienced in some cases in interrupting very large currents. It has been found that the arc does not always readily transfer from a single long arc playing through the 45 slot to a series of short arcs playing between the plates. It has sometimes been found that the arc does not transfer to the plates until the current in the arc dies down during the alternating current cycle to some lower value of current. During the 50 time that the arc current is high, it may partially transfer to the plates and then transfer back into the slot through the plates. In some cases, this results in a constant motion of the arc back and forth over the end of the slot through the plates, 55 so as to cause excessive burning of the tip of the slot. After the arc has been split up into short arcs between the plates, there is a tendency, when the arc carries very large currents, for it to reignite in the entrance slot as the voltage again 60 builds up after a current zero, even though the

arc which transferred to the plates has been extinguished, due to the fact that there may be ionized gas present in the slots through the plates. That is, the arc may jump back into the slot after it has once transferred to the plates and been 5 extinguished there.

By making use of this invention, the amount of current which can be made to transfer to the plates can be greatly increased thus making it possible to build a circuit breaker of this type of much higher interrupting ability. This is accomplished by making use of a double plate having two annular paths with a single slot having two diverging branches, each of which leads into one of the annular paths. The arc is moved upwardly 15 in the slot and into the diverging branches where the arc plays as two parallel-connected arcs. Each of these parallel-connected arcs is then moved further along in its branch of the slot until the tips of the slots are reached when each of the 20 parallel-connected arcs is split up into a plurality of series-connected arcs between the plates. Each of these arcs is then rotated about the annular paths between the plates until they are extinguished. 25

An unrestricted arc playing in air cannot normally be caused to play in two parallel-connected sections due to the fact that such an arc has a drooping voltage characteristic. That is, the arc voltage decreases as the current increases. It has been found possible to make the arc play in a stable condition as two parallel-connected arcs 30 by causing it to have a rising voltage characteristic wherein the arc voltage increases as the current increases. This rising arc-voltage characteristic causes the arc to divide when it reaches the branching portions of the slots and also tends to make the current divide evenly between the two 35 arcs.

This change from a drooping arc-voltage characteristic to a rising arc-voltage characteristic is accomplished by moving the arc into a restricted slot in the plates which reduces the cross section of the arc and causes it to play with a higher current density and a higher arc voltage than 40 would an unrestricted arc.

These and other objects of the invention will more fully appear from the following description of the preferred embodiment of my invention illustrated in the drawings in which:

Figure 1 shows a view partly in section and partly in elevation of the arc extinguisher of my invention; the section being enlarged and taken through the stack of plates on the line I—I of 45 Fig. 4.

Fig. 2 is a cross sectional view through the arc extinguisher of Fig. 1 taken on the line II—II of 50 Fig. 1.

Fig. 3 is a cross sectional view through the arc 55

extinguisher of Fig. 1 taken on the line III—III of Fig. 1.

Fig. 4 is a cross sectional view taken on the line IV—IV of Fig. 1, and shows the radial field coils 5 which rotate the arc.

Fig. 5 is a sectional view through one of the radial field coil groups taken on the line V—V of Fig. 4.

Fig. 6 is an exploded view of the group of arc transfer plates used with each of the radial-field-coil groups; and,

Figs. 7 and 8 are views partly in section and partly in elevation and show the assembly of the conducting plates which provide annular paths 15 about which the arc may be rotated within the iron plates for magnetically moving the arc.

The line terminals 11 and 13 of the circuit breaker are connected to the stationary arcing contact 15 and the moving arcing contact 17. 20 The moving contact 17 may be actuated to open position by any suitable type of operating mechanism which may be provided with main contacts for normally completing the circuit through the circuit breaker. Directly above the stationary 25 and moving arcing contacts 15 and 17 are positioned arc horns 19 and 21. The stationary contact 15 is supported from the arc horn 19 but insulated therefrom by a block of insulating material 23. The arc horns 19 and 21 are provided 30 with up-standing portions 24 and 25 respectively which form the ends of the arc extinguishing structure. The arc horns 19 and 21 and their up-standing end portions 24 and 25 are of iron and have copper end plates 27 and 29 positioned 35 on their sides which face each other.

The arc extinguishing structure between the end plates comprises a plurality of plate groups 31 and 33 which are alternated along the stack. While the drawings show two plate groups 31 with 40 one plate group 33 therebetween, it is understood that for higher voltages a larger number of plate groups will be used. Between adjacent plate groups there are positioned radial-field-coil groups 35 for providing a radial magnetic field for 45 rotating the arcs between the plates.

Each of the plate groups 31 is made up of an assembly of iron, copper and insulating plates as illustrated in Figs. 2 and 8. A composite plate is formed by positioning a plate 37 of conducting material such as copper within a plate 39 of a magnetic material such as iron. The copper plate 37 is shaped so as to provide a pair of annular portions disposed side by side with round holes 41 through the center of each of the annular portions. The lower portion of each of the conducting plates 37 is provided with a projecting portion 40 extending below the lower edges of all of the other plates in the stack. This extending portion 40 is provided with a slot 42 having two diverging branches 43 and 45 which lead into the annular portion of the plates tangentially thereto. The provision of the extension 40 makes it possible to provide a relatively long slot 42 before the branches 43 and 45 are reached. The slot 60 42 is narrower than the arc so that the arc is restricted in cross section and caused to have a higher arc voltage and a rising arc-voltage characteristic.

The plates 39 of magnetic material have a cut- 70 out portion which has the same shape as the outer periphery of the conducting plates 37, so that the conducting plates exactly fit within the iron plates. The iron plates 39 therefore act as an extension of the conducting plates 37 and 75 provide additional heat capacity for taking up

the heat of the arc. The iron plates thus extend around three sides of the copper plates, but have an opening providing an air gap across the lower portion of the slots therein. The iron plates 39 have extensions 47 (Figs. 7 and 8) in the form 5 of separate iron plates insulated by paper sheets 48 (Figs. 2 and 3). The stack of plates 47 and 48 are faced with a member of arc resisting insulating material 49. The arc is drawn by the contacts 15 and 17 between the iron plates 47 10 and is moved upwardly in the slots in the copper plates due to the distortion of the magnetic field by the generally U-shaped pole pieces formed by the iron plates 39 and their extensions 47.

The composite plates formed by the conduct- 15 ing plates 37 and the magnetic plates 39 are spaced apart by sheets of insulating material such as fish paper which are shaped as illustrated in Fig. 1. There are two sheets of insulation between adjacent conducting and magnetic plates. 20 The complete insulating plates 51 have a pair of annular openings 53 cut therein and diverging slots 55 and 56 leading tangentially into each of the annular openings 53. The annular openings 53 in the complete insulating plates 51 fit over 25 the annular portions of the conducting plates 37 so as to provide a complete annular path about which the arcs may be rotated. The edges of the annular openings 53 extend over the joint 30 between the conducting plates 37 and the magnetic plates 39 so as to prevent the arc from playing through the crack between the two plates.

The composite plate formed by the conducting plates 37 and the magnetic plates 39 are also 35 spaced apart by vented insulating plates made up of three portions 57, 59 and 61. The vented plates when assembled together are of the same shape as the complete plates 51, except that a portion leading from the top of each of the annular arc paths to the top of the plates is cut out, 40 so as to provide a vent from the annular arc space, through which the hot arc gases may escape. By having the conducting plates 37 and magnetic plates 39 spaced apart by the two types 45 of plates of insulating material, one of which defines the complete annular arc path and the other of which has a ventilating passage extending from each arc path, it is made impossible for the arc to move out of the annular path and into 50 the vent extending from each of the annular arc paths.

The plates of the alternate plate groups 33 are 55 of the same general type as those of the plate groups 31, except that they are designed for rotation of the arc in the direction opposite to the direction of rotation of the arcs in the plate groups 31. As shown in Fig. 7, the conducting plates 63 each have two annular portions each having an opening 65 through the center thereof. The slot 66 in the conducting plates 63 extends 60 upwardly between the two annular portions of the plates and has two diverging branches 67 and 69 which extend tangentially into the annular portions of the plates. The slots 67 and 69 65 lead into the top of the annular portions of the plates whereas the slots 43 and 45 in the conducting plates 47 of the plate groups 31 lead into the bottom of the annular portions of the plates. It is not necessary that the conducting plates 70 63 in groups 33 have extensions corresponding to the extensions 40 of conducting plates 37 in the groups 31, since the slot 66 extending between the annular paths to the top portion thereof is sufficiently long to reduce the cross section and 75

increase the arc voltage of the arc before it is split up.

Each of the conducting plates 63 is surrounded by a plate 71 of magnetic material, such as iron, which has a cutout portion shaped to fit around the outer periphery of the conducting plates 63. The magnetic plates 71 in the plate groups 33 function in the same manner as the magnetic plates 39 in the plate groups 31.

The conducting plates 63 and magnetic plates 71 of plate groups 33 are spaced apart by complete insulating plates 73 (shown in Fig. 3) which have a pair of annular cutout portions 75. The insulating plates 73 also have a slot extending upwardly between the two annular cutout portions 75 with diverging branches 77 which are shaped similarly to but are wider than the branches 67 and 69 of the slot in the conducting plates 63. The conducting plates 63 and magnetic plates 71 are also spaced apart by vented plates formed of three parts 79, 81 and 83 which together make up a plate of the same shape as the complete plates 73, except that they have portions cut away providing a ventilating passage extending from each of the annular arc paths to the top of the plates.

The conducting plates 37 and 63 of both plate groups are also spaced apart by washers 82 of insulating material positioned around the holes 41 and 65. A slot 84 extends into each of the openings 41 and 65 to reduce eddy current losses. The two slots 84 in each plate are at right angles to each other so that the slots in adjacent plates may be kept out of alignment by reversing adjacent plates.

Each of the radial-field-coil groups 35 is made up of a pair of coils 85 and 87 wound from copper strap, as illustrated in Figs. 4 and 5. The two coils are connected together at one end so as to form a double coil with each half of the coil wound in opposite directions. This double coil is positioned between a pair of coil-end plates 89 and 91 and the free end of one coil is connected to the plate 89 and the free end of the other coil is connected to the plate 91 so that double coil is electrically connected in series between the coil end plates 89 and 91. Each of the coil end plates is surrounded by a magnetic plate 93. The space between the magnetic plates 93 is filled in at the top of the plates by a rectangular block of insulating material 95 and at the sides by angularly shaped blocks of insulating material 97.

A plurality of arc-transfer plates (Figs. 1, 4 and 6) are positioned beneath the center of the space between the two coils 85 and 87. The center plate 98 of the group of arc-transfer plates is shaped as shown in Fig. 6, and is unslotted. The arc-transfer plates 99 positioned on the side of the center plate 98 toward the plate groups 31 are provided with double slots 100, while the arc-transfer plates 101 on the side of the center plate 98 which face the plate groups 33 are provided with a single slot 102. The end arc-transfer plates 103 and 104 are cut off at their tops, while the other arc transfer plates 98, 99 and 101 have extensions which extend up between the coils 85 and 87. The end arc transfer plates 103 and 104 have slots 102 and 100 respectively the same as plates 101 and 99. The arc transfer plates are spaced apart by members 105 of sheet insulating material.

The alternate plate groups 31 and 33 with the radial-field-coil groups 35 positioned therebetween are assembled between the end plates 23 and 25, and the stack is secured together by in-

sulating tie rods 119 which have threaded metal end pieces 123 on which are screwed nuts 124. The various conducting, magnetic and insulating plates are held in their proper relations by means of pins 121 of insulating material which extend through suitable openings 122 in all of the plates. An insulating tube 125 extends through the aligned openings 41 and 65 in the conducting plates 37 and 63. Positioned within each of the insulating tubes 125 is a slotted tube 127 of magnetic material such as iron to provide a core for the magnetizing coils 85 and 87 and thereby aid in distributing the flux along the length of the stack of plates.

A rod 129 of copper extends through the inside of one of the tubes 127 and a rod 131 through the other of the tubes 127. One line terminal 11 is connected through a conductor 130, as shown in Fig. 1, to the left-hand end of rod 131. The other end of rod 131 is connected by means of a conductor 133 to the right-hand end of a rod 135 which extends through an insulating tube 137 extending through the top portions of the insulating blocks 95. The other end of the rod 135 is connected by a conductor 139 to the left-hand end of the rod 129 which has its right-hand end connected by conductors 141 and 143 to the arc horn 19.

The current normally flows from the line terminal 11 through the contacts 15 and 17 to the line terminal 13. When this circuit is broken by the separation of the arcing contacts 15 and 17, the path of the current is then as indicated by the arrows, with the current flowing during one half cycle of the alternating current wave from line terminal 11 through conductor 130, rod 131 through the stack of plates, conductor 133, back across the stack through rod 135, to conductor 139 which is connected to the other rod 129 which carries the current through the center of the other annular arc path in the same direction as the current flow in the rod 131. The circuit from the rod 129 is completed by the conductor 141 and 143 to the arc horn 19. The current then flows through the arc from the arc horn 19 to the arc horn 21 which is connected to the other line terminal 13.

It should be noted that the direction of current flow is the same through both of the rods 129 and 131 which, together with the other conductors, form a two-turn coil surrounding the magnetic plates 39 and 71 for setting up a magnetic field in the magnetic plates which moves the arc up into the slots in the conducting plates 37 and 63. Since the direction of current flow in the arc from the arc horn 19 to the arc horn 21 is the same as the direction of the current flow through the rods 129 and 131, the arc is attracted to the conductors and moved toward the center of each of the arc paths.

As the arc is moved upwardly on the arc horns 19 and 21 into the stack of plates, the arc first encounters the extensions 40 on plates 31. As the arc moves up the slots 42 in the extensions 40, it is reduced in cross section, thereby causing it to play with a higher current density and a higher arc voltage. The arc is then split up into a series of sections between the center unslotted arc-transfer plates 98. Each of the arc sections is then moved upwardly. In the plate groups 31 the arc is divided longitudinally into two parallel-related arcs by the two slots 100 in the arc-transfer plates and the slots 43 and 45 in the plates 37, while in the alternate plate groups 33

the arc continues to play for a while as a single arc.

After the arcs reach the tips of the slots 100 and 102 in the arc-transfer plates, the ends of the 5 arc sections are transferred to the coil-end plates 89 and 91 so that the radial field coils 85 and 87 are electrically connected in series with the arc sections. The coils 85 and 87 then set up a radial 10 magnetic field about each of the annular arc paths and also across the slots 43, 45 in plates 37, and across slots 66, 67 and 69 in plates 63. In each of the plate groups 31 the sense of the 15 radial field is in such direction as to cause the arc to rotate clockwise (Fig. 2) about the left-hand annular path and counter-clockwise about the right-hand annular path. In the plate groups 33 the magnetic field is of opposite sense to the magnetic field in the plate groups 31, so that the arc will be rotated counter-clockwise 20 (Fig. 3) about the left-hand annular path and clockwise about the right-hand annular path.

In the plate groups 31, the radial field moves the arc up into the slots 43 and 45 which are of 25 decreasing width so as to further restrict the cross section of the arc and increase its current density and make it play with a higher arc voltage and a rising arc voltage characteristic. When the parallel-related arcs reach the tips of the 30 slots 43 and 45, they are each split up into a plurality of short series-related arcs between the plates which are rotated therebetween until extinguished.

In the plate groups 33, the arc is moved upwardly as a single arc in each group in the slots 35 66 by the radial field. The slots 66 restrict the arc and cause it to play with a rising arc-voltage 40 characteristic so that it will play as two parallel-related arcs when the junction of the two branches 67 and 69 are reached. The two parallel-related arcs are moved by the radial field up 45 the slots 67 and 69 and are further restricted in cross section and the current density is increased. This makes it easier for each of the two parallel-related arcs to be split up into a large number of 50 short series-related arcs when the tips of the slots are reached. These short arcs are rotated between the plates until a current zero is reached when they are extinguished.

From the foregoing detailed description of a 55 specific embodiment of the invention, it is apparent that the structure of this invention provides an arc extinguisher for a circuit breaker which is capable of extinguishing arcs carrying very heavy currents. This is accomplished by 60 first splitting the arc longitudinally into a pair of parallel-connected arcs and then separately extinguishing each of the parallel-connected arcs. It should be noted that the arc is split into a pair 65 of parallel connected arcs for the whole length of the arc between its terminals. This is accomplished by providing coil-end plates at the end of each group of plates, which form arc terminal members having two diverging branches along which each of the parallel-connected arcs 70 is moved. The plates of insulating material provided between the conducting plates also provide an arc path through the structure having two diverging branches, so that the insulating plates also cause the arc to be split longitudinally into parallel-connected arcs.

Each of the conducting plates is provided with a pair of annular portions defined by the insulating plates. These annular arc paths are positioned side-by-side so that there are two arcs 75 which play on each plate as the arcs are rotated.

The pairs of arc paths between each pair of conducting plates and between each pair of coil-end plates are electrically connected in parallel since the two annular paths are on an integral plate. It would, of course, be possible to have each 5 annular arc path on a separate conducting plate with the plates on which each arc is rotated electrically connected to the plates on which its parallel-related arc is rotated.

The circuit breaker of this invention first establishes a single arc which is split longitudinally into parallel-related arcs. These parallel-related arcs are moved in diverging slots having diverging arc terminals at the ends thereof. Each of these parallel-connected arcs are then split cross-wise into a plurality of series-related arcs. These parallel and series-related arc sections are then moved into the annular arc paths defined on the copper plates by the insulating plates and are rotated. The two parallel-related portions of the 20 arc in each group of plates are rotated in opposite directions by the magnetic field. That is, if the portion of the arc in any one group of plates of the arc extinguisher is rotated clockwise, the parallel portion of the arc in the same 25 group of plates is rotated counter-clockwise. The arc is also rotated in opposite directions in alternate groups of plates so that if one section of one of the arcs is rotated clockwise in one group of plates the adjacent sections of the arc in the 30 groups of plates on each side thereof, which are in series with the portion which is rotated clockwise, are rotated counter-clockwise. It is apparent that the arc extinguisher of this invention divides the arc into a multitude of very small 35 sections which are rotated in different directions in contact with a large area of cool material, so that the arc is readily extinguished.

There is also an important advantage in splitting the arc longitudinally into a plurality of 40 parallel-related arcs prior to splitting up the arc cross-wise into short arcs. This is due to the fact that it is very difficult to move a heavy current arc into a series of spaced plates between which the arc is to be split into a plurality of series-related arcs without burning the edge of the plates where the arc is moved into them. By first splitting the arc longitudinally into two parallel-related arcs, each of these arcs carries only half the current and may be split up into 50 short series-related arcs much more easily without damage to the plates.

While a specific embodiment of the invention has been described in detail, it is apparent that various modifications can be made without departing from the spirit of the invention.

I claim as my invention:

1. In a circuit interrupter, means for establishing a single arc, means for splitting the arc lengthwise into a plurality of parallel-related 60 arcs and means for splitting each of the plurality of arcs crosswise into a plurality of series-related arcs.

2. In a circuit interrupter, means for establishing a single arc, means for splitting the arc 65 lengthwise into a plurality of parallel-related arcs and means for splitting each of the plurality of arcs crosswise into a plurality of series-related arcs, and means for moving a plurality of the parallel and series-related arcs over recurrent 70 paths.

3. In a circuit interrupter, means for establishing a single arc, means for splitting the arc lengthwise into a plurality of parallel-related 75 arcs and means for splitting each of the plurality of arcs crosswise into a plurality of series-related arcs.

of arcs crosswise into a plurality of series-related arcs, and means for setting up a magnetic field for rotating a plurality of the parallel and series-related arcs about annular paths.

4. In an arc extinguisher, means providing a terminal for the arc, said arc terminal means providing a path for one end of the arc, said terminal means having at least two branches leading therefrom, and means for moving the arc along said arc terminal means and onto said branches and causing the arc to split into two separate parallel-connected arcs.

5. In an arc extinguisher, means providing a terminal for the arc, said arc terminal means providing a path for one end of the arc and having at least two branches leading therefrom, and means for moving the arc along said arc terminal means and onto said branches and causing the arc to split into two separate parallel-connected arcs, and arc extinguishing means for the separate arc playing on each branch.

6. In an arc extinguisher, means providing a terminal for the arc, said arc terminal means providing a path for one end of the arc and having at least two branches leading therefrom, and means for moving the arc along said arc terminal means and onto said branches and causing the arc to split into two separate parallel-connected arcs, and a plurality of conducting members into which the arc playing on each branch is moved.

7. In an arc extinguisher, means providing a terminal for the arc, said arc terminal means providing a path for one end of the arc having at least two branches leading therefrom, and means for moving the arc along said arc terminal means and onto said branches and causing the arc to split into two separate parallel-connected arcs, and a plurality of cooling members into which the arc playing on each branch is moved.

8. In a circuit interrupter, means having a plurality of passages therein, said passages being joined together at one end and diverging at the other end, arc terminal means for said passages, means for causing an arc to play adjacent the juncture of said passages, means for moving the ends of the arc on said arc terminal means toward the diverging ends of the passages and causing the arc to play along its whole length as a plurality of parallel-connected arcs.

9. In a circuit interrupter, means having a plurality of passages therein, said passages being joined together at one end and diverging at the other end, arc terminal means for each of said passages, means for causing an arc to play adjacent the juncture of said passages, means for moving the ends of the arc on said arc terminal means toward the diverging ends of the passages and causing the arc to play along its whole length as a plurality of parallel-connected arcs, and means for splitting up each of said parallel-connected arcs into a plurality of series-connected arcs.

10. In a circuit interrupter, means having a plurality of passages therein, said passages being joined together at one end and diverging at the other end, arc terminal means for each of said passages, means for causing an arc to play adjacent the juncture of said passages, means for moving the ends of the arc on said arc terminal means toward the diverging ends of the passages and causing the arc to play along its whole length as a plurality of parallel-connected arcs, and means for splitting up each of said

parallel-connected arcs into a plurality of series-connected arcs, and means for rotating said plurality of series and parallel-connected arcs over recurrent annular paths.

11. In an arc extinguisher, a plurality of sheet members having slots therein, each of said slots having a plurality of diverging branches, and means for causing movement of the arc in said slots up said diverging branches to form a plurality of separate arcs.

12. In an arc extinguishing structure, means providing a single arc path, means providing a pair of arc paths including terminal means at the ends of each arc path electrically connected in parallel with the terminal means of the other arc path, means for causing a single arc playing in said single arc path to divide to form a pair of parallel-connected arcs and to play with one arc in each of said parallel paths, and means for causing a radial magnetic field of opposite sense across each of said pair of paths for rotating the arcs.

13. In an arc extinguishing structure, means providing a pair of arc paths each having terminal means at the ends thereof electrically connected in parallel with the terminal means of the other arc path, and means for establishing an arc and causing it to be split into a plurality of arcs playing between said parallel connected terminal means.

14. In an arc extinguisher, a plurality of conducting members, each of said conducting members having a pair of annular portions disposed side by side, means for establishing an arc, means for causing the arc to play in two parts, and means for causing each part of the arc to rotate about one of the annular portions of the conducting members.

15. In an arc extinguisher, a plurality of conducting members, each of said conducting members providing a pair of arc paths thereon disposed side by side, means for establishing a single arc, means for causing said arc to split and play in each of said arc paths as separate arcs and means for moving each arc along its arc path.

16. In an arc extinguisher, a plurality of conducting members, each of said conducting members having a pair of annular portions disposed side by side, and means of magnetic material extending around three sides of both of said annular portions for moving the arc thereinto.

17. In an arc extinguisher, a plurality of conducting members, each of said conducting members having a pair of annular portions disposed side by side, and means of magnetic material extending around three sides of both of said annular portions for moving the arc thereinto and conducting means extending through the center of each of said annular portions for energizing said means of magnetic material.

18. In an arc extinguisher, a plurality of conducting members, each of said conducting members having a pair of annular portions disposed side by side, and each of said conducting members having a slot therein, said slots having diverging branches each of which extends toward one of said annular portions of the conducting members.

19. In an arc extinguisher, a plurality of conducting members, each of said conducting members having a pair of annular portions disposed side by side, and each of said conducting members having a slot therein, said slots having diverging branches each of which extends toward

- one of said annular portions of the conducting members, means for moving the arc along said slot and into said diverging branches and splitting it into parallel connected sections, and means 5 for rotating each of said arc sections around one of the annular portions of the conducting members.
20. In an arc extinguisher, a plurality of sheet members of insulating material having an opening therein in which the arc is caused to play, 10 said opening having a plurality of slots leading therefrom, and means for moving the arc into said slots and causing it to play as a plurality of parallel connected arcs.
- 15 21. In an arc extinguisher, a plurality of sheet members of insulating material having an opening therein in which the arc is caused to play, said opening having a plurality of slots leading therefrom, each of a plurality of said sheet members having a plurality of annular openings therethrough into each of which one of said slots extends, 20 and means for rotating the arc about said annular openings.
22. In an arc extinguisher, a plurality of sheet members of insulating material having an opening therein in which the arc is caused to play, 25 said opening having a plurality of slots leading therefrom, and ventilating spaces extending from between said members of insulating material to the outside thereof.
23. In an arc extinguisher, a plurality of sheet members of insulating material having an opening therein in which the arc is caused to play, 30 said opening having a plurality of slots leading therefrom, for splitting the arc into a plurality of parallel connected parts, and each of a plurality of said members of insulating material having a plurality of annular openings therethrough into each of which one of said slots extends, 35 conducting means in each of said annular openings for splitting up the arc therein into a plurality of series connected parts, and means for rotating all of said arcs in said annular openings.
24. The method of extinguishing an arc which 40 comprises separating the arc into a plurality of parallel arcs and moving each arc in a direction different from another of said parallel arcs.
25. The method of extinguishing an arc which 45 comprises separating the arc into a plurality of parallel arcs and moving each arc along a different recurrent path.
26. The method of extinguishing an arc which 50 comprises drawing said arc between a pair of members, splitting said arc into two parallel arc sections, splitting each of said parallel arc sections into a series of shorter arcs and moving the shorter arcs of each section along curved paths, the direction of movement of the shorter arcs of one section being opposite to the direction of 55 movement of the shorter arcs of the other section.
27. The method of extinguishing an arc which 60 comprises splitting the arc lengthwise into a plurality of parallel related arcs, splitting each parallel related arc crosswise into a plurality of series related arcs and rotating the series related arcs 65 of each parallel related arc over different recurrent paths.
28. The method of extinguishing an arc which 70 comprises drawing said arc between a pair of members, increasing the current density of said arc, moving said arc along diverging paths to form two parallel arcs and rotating one of the arcs in a direction opposite to the other of said arcs.
29. The method of extinguishing an arc which 75 comprises drawing said arc between a pair of members, increasing the current density of said arc, moving said arc along diverging paths to form two parallel arcs, splitting each of said parallel arcs into a plurality of serially related arcs and rotating said serially related arcs over recurrent paths, the direction of rotation of some of said serially related arcs being opposite to that of other of said serially related arcs. 80
30. An arc extinguisher comprising a pair of movable members between which an arc may be drawn, a plurality of spaced conducting plates having slots therein terminating in a pair of diverging branches, said slots being alined to form a Y-shaped groove, means to drive the arc into said groove in a direction toward the diverging branches for causing it to separate into two parallel arc sections, and means for moving each arc section from the terminating end of its respective branch into said conducting plates to sub-divide each arc section into a plurality of serially related arcs playing between said plates. 85
31. An arc extinguisher comprising a pair of movable members between which an arc may be 90 drawn, a plurality of spaced conducting plates having a pair of annular arc conducting portions disposed side by side, each of said conducting plates having a slot therein, said slots having diverging branches, each of which extends toward one of said annular arc conducting portions, means to drive the arc into said slots and into said diverging branches for splitting it in two parallel connected sections, and means to produce radial magnetic fields in said plates for rotating each of said arc sections around one of 95 said annular conducting portions.
32. An arc extinguisher comprising a pair of movable members between which an arc may be drawn, a plurality of spaced conducting plates 100 having a pair of annular arc conducting portions disposed side by side, each of said conducting plates having a slot therein, said slots having diverging branches, each of which extends toward one of said annular arc conducting portions, means to drive the arc into said slots and into 105 said diverging branches for splitting it in two parallel connected sections, and means to produce radial magnetic fields of opposite polarity 110 about the annular conducting portions for rotating each of said arc sections around one of said conducting portions to thereby separate said arc sections into a plurality of serially related 115 arcs.
33. In combination with means for establishing an arc between a single pair of terminals, 120 means defining a path for constricting said arc, means defining other paths into which portions of said arc may be moved and which also tend to constrict the arc portions playing therein, and means for moving said arc into said path and for causing it to split longitudinally into parallel 125 portions which play respectively within said other paths.
34. In combination with a single pair of terminals adapted to draw an arc, side walls forming 130 a constricting slot having a main portion and a plurality of branches, means for forcing said arc to play within said main portion and to then split longitudinally and its subdivisions to play 135 separately within said branches.

FREDERICK B. JOHNSON.
